CLAIM

The ornamental design for body part warming device, as shown and described.

DESCRIPTION

FIG. 1 is a back elevational view of a body part warming device showing my new design;

FIG. 2 is a back elevational view thereof;

FIG. 3 is a right side elevational view thereof;

FIG. 4 is a top plan view thereof;

FIG. 5 is a bottom plan view thereof;

FIG. 6 is an isometric view thereof; and,

FIG. 7 is a front view thereof, in use.

The dashed lines shown directly on the surface of the claimed article, throughout the views, are understood to represent stitching.

The broken line showing of a human figure is included for the purpose of illustrating environmental structure and forms no part of the claimed design.
